[57] CLAIM

The ornamental design for a bumper protecting trailer hitch guard, as shown and described.

DESCRIPTION

FIG. 1 is a side perspective view of a bumper protecting trailer hitch guard showing our new design, the broken lines are for illustrative purposes only and form no part of the claimed design;

FIG. 2 is a side elevational view thereof, the opposite side being a mirror image thereof;

FIG. 3 is a front elevational view thereof;

FIG. 4 is a top plan view thereof;

FIG. 5 is a rear elevational view thereof; and,

FIG. 6 is a bottom plan view thereof.
